Specification for Design.

Patented Dec. 14, 1920.

Application filed October 2, 1919. Serial No. 328,072. Term of patent 7 years.

To all whom it may concern:

Be it known that I, FREDERIK G. WHITTINGTON, a citizen of the United States, and a resident of the city of Chicago, in the county of Cook and the State of Illinois, have invented a new, original and ornamental Design for a Lamp-Bracket, of which the following is a specification, reference being had to the accompanying drawings, forming a part thereof.

In the drawings:

Figure 1 is a front elevation of a lamp bracket embodying this design.

Fig. 2 is a side elevation of the same.

I claim:

The ornamental design for a lamp bracket as shown.

In testimony whereof, I have hereunto set my hand at Chicago, Illinois, this 29th day of September, 1919.

FREDERIK G. WHITTINGTON.
